UNITED STATES PATENT OFFICE.

VANDIVER J. VAN HORN, OF CHICAGO, ILLINOIS, ASSIGNOR OF ONE-HALF TO JOHN W. O'NEILL, OF CHICAGO, ILLINOIS.

FEED MECHANISM FOR SEWING-MACHINES.

1,060,799.

Specification of Letters Patent.

Patented May 6, 1913.

Application filed August 7, 1911. Serial No. 642,762.

To all whom it may concern:

Be it known that I, VANDIVER J. VAN HORN, a citizen of the United States, residing at Chicago, in the county of Cook and 5 State of Illinois, have invented certain new and useful Improvements in Feed Mechanism for Sewing-Machines, of which the following is a specification.

The present invention relates to feed- 10 mechanism which is adapted for use in sewing machines generally, but which is particularly adapted for use in machines used for sewing heavy goods or a number of superposed sheets or plies. It is also adapted 15 for use in machines having only a single needle, but is particularly adapted for use in machines having a plurality of needles for simultaneously making a plurality of parallel seams.

20 A large number of needles are used in machines for quilting purposes, but since the use of any number of needles more than one involves largely the mere duplication of parts, for the sake of brevity the following 25 description will be confined to a machine having only a single needle, excepting when it becomes necessary to refer to accessory parts that are peculiar to machines having a plurality of needles.

30 The improved feed mechanism is also particularly adapted for use in machines to which the goods to be worked up are fed continuously as, for example, by being unwound from bolts or rolls, or otherwise, and 35 which turn out the finished work in indefinite lengths, of uniform character, which, in turn, is used as stock and cut up as desired for making various articles. For example, that class of quilting used in garments for 40 padding and other purposes usually consists of inner and outer sheets or plies of fabric and an inner sheet or ply (or plies) of batting or other padding material. The outer plies are continuous and are usually fed to 45 the quilting machine as they are unwound from bolts or rolls, while the padding is usually laid on the lower outer ply as it traverses a table before reaching the needles, but it is manifest that if desired, the padding also may be unwound from the bolt or 50 roll, if its character will permit. At any rate, the quilting has a plurality of plies and, stated in general terms, the principal objects of the present invention are to pro-

vide, for use in sewing machines of any of 55 the characters above mentioned, a feed mechanism which will insure the absolutely uniform and equal feeding of all of the several plies of goods to the machine and a similar delivery of the completed work by 60 the machine, at the same time avoiding all lateral strains upon the needle and all undue or objectionable stretching of the goods or the completed work, to the end that 65 its normal condition is flat and without 70 pockers or the like. In order to accomplish these objects, the feed mechanism of the present invention is so constructed that while the needle is above or out of the work, a sufficient length of the work for at least 75 one stitch (preferably the exact length that is necessary—no more and no less) is fed or drawn forward past the path of the needle. This feeding takes place while the 80 needle is making the last half (or other proportional part) of its up-stroke and the first half (or other proportional part) of its down-stroke and is out of the work, while 85 that portion of the work which lies in the path of the needle remains at rest while the 90 needle is completing its strokes. This feeding (by which is meant the forward movement) of the work is produced in part by a device herein called a "deflector" which engages the work in rear of the needle while 95 the needle is up—out of the work,—and completes its part of the feeding operation before the needle again enters the work said 100 deflector being capable of reciprocating movements across the general plane of the work as it passes through the machine and in directions transverse to said plane. The entire feeding operation must be completed while the needle is out of the work in order 105 that lateral strains upon the needle or the stretching of the work in rear of the needle will be avoided, but it is immaterial, so far as the carrying out of the broad idea of the invention is concerned, whether the deflector thereupon wholly disengages the work and allows it to become perfectly slack in rear of the needle, or remains in engagement with the work in such a manner as to simply hold the work taut (but not under any considerable tension) preventing the formation 110 of any considerable amount of slack in rear of the needle. Furthermore, whatever slack is formed is gradually and continuously

taken up by a pair of rolls which are, in fact, a part of the feeding mechanism and perform the double function of a slack take-up by reason of their rotation and a clamp by reason of their being forced toward each other, both of which are necessary in the carrying out of the invention. The expression "not under any considerable tension" is intended to mean that the work is not under sufficient tension to draw it past the needle. It is, of course, a physical impossibility with the parts so arranged that the work normally occupies a substantially horizontal position, to absolutely eliminate tension, because the weight of the work itself will of necessity produce a very slight tension.

In those forms of the invention which have been selected for the purpose of this application, the feed mechanism considered as a whole, includes the aforesaid rolls and the aforesaid deflector which is adapted to engage the work and cross it transversely, from side to side, at a point between the needle and the rolls, said deflector being movable in a direction which is transverse to the normal plane of the work. The work being constantly and firmly clamped by the rolls so as to hold it at all times against retrograde movement, after the deflector, while moving downward, comes in contact with the work, its continued downward movement will draw forward a length of the work sufficient for the next stitch, and when the needle, moving downward, reaches the work the deflector will immediately commence, or will have commenced and partially completed, its up-stroke, so that the length of the work thus actually drawn forward by the deflector will be taken up by the rolls, which are constantly driven at such surface speed that they will take up the work only as fast as it is actually fed forward by the deflector. If the deflector at any time moves away from and entirely out of contact with the work, there will be an unrestrained slack between the needle and the rolls, but by so relating the needle-bar and deflector that the point of the needle moves both above and below the normal plane of the upper surface of the work, while the engaging face of the deflector never passes above said plane, and by limiting the movement of the deflector to exactly what is required for feeding forward the exact length of the work necessary for a single stitch, said deflector will remain constantly in contact with the upper surface of the work and hold it taut, but not under tension, between the needle and the rolls.

The object of the invention is to provide a feed mechanism having the above described mode of operation and to this end the invention consists in the features of novelty that are hereinafter described with reference to the accompanying drawings, which

are made a part of this specification, and in which:

Figure 1 is an elevation, on an enlarged scale, of a feed mechanism for sewing machines embodying the invention and so many of the parts of the machine as are necessary in order to fully understand the same, the parts being viewed in the direction of the arrow, 1, Fig. 2, *i. e.*, looking toward the face-plate end out of the machine head, but with the face-plate omitted. Fig. 2 is an elevation thereof viewed in the direction of the arrow 2, Fig. 1, *i. e.*, looking forward from the rear side of the machine head. Figs. 3, 4, 5, and 6 are diagrammatic views of the principal parts of the feed mechanism, showing the parts in the positions which they occupy at four successive equidistant stages in the complete cycle of movement involved in making the two complete upward and downward strokes of the needle-bar, necessary in the making of a single stitch. Figs. 7, 8, 9 and 10 are diagrammatic views similar to Figs. 3, 4, 5 and 6 involving the principle or the fundamental idea of the invention as carried out by a modification in the construction and arrangement of the parts. Fig. 11 is a plan view of the machine head, all parts below the top of the head being omitted, for the sake of clearness. Fig. 12 is a horizontal section on the line 12-12, Fig. 1, looking downward. Fig. 13 is a horizontal section on the line 13-13, Fig. 1, looking downward. Figs. 14 and 15 are detailed views of a modification.

The preferred form of the invention will be first described and thereafter the modifications will be considered, but in all forms of the invention corresponding parts are indicated by similar reference characters.

The main shaft, 1, of the machine head carries a disk or wheel, 2, which, in turn carries an eccentrically located crank-pin, 3, which occupies an eye in one end of a link, 110 or pitman, 4, the other end of which is occupied by a pin, 5, projecting from a collar, 6, adjustably secured to the needle-bar, 7, to the lower end of which the needle, 8, is secured by a clamp 8^b of any known or desired construction.

The thread take-up and tension devices form no part of the present invention and need not be described.

The presser-foot, 10, is carried by a presser-bar, 11, which is impelled downward by a spring, 12, the tension of which may be regulated by a screw, 13, but the details in the construction of this presser-foot mechanism form no part of the present invention and need no further description. The presser-foot operates in conjunction with a portion of the base-plate of the head, or a slide secured thereto, either of which may be considered as represented by the part 130

numbered 14 on the drawings, but unlike the presser-foot of an ordinary sewing machine it does not cooperate with a toothed or serrated reciprocating feed device.

5 In rear of the presser-foot bar is located a bar, 15, hereinafter called the feed-bar, having or carrying at its lower end a part hereinafter called the deflector, the working, or extreme lower, surface of which is 10 rounded off so as to present a smooth surface for contact with the work. The needle-bar, the presser-foot bar, and the feed-bar are all parallel with each other and lie in the same vertical plane, and each is capable of vertical reciprocation transversely 15 to the general plane of the work as it passes through the machine, each being guided by suitable bearings which are attached to or formed with the machine head, the bearings 20 for the feed-bar being shown at 17 and 18.

The feed-bar is carried by a collar, 19, which is adjustable thereon for the purpose of enabling the adjustment of the deflector to any elevation relative to the other parts 25 of the feed mechanism whereby the deflector may be made to accommodate goods of different thickness and whereby the range of its movement may be set at any elevation relative to the other parts. The collar is 30 jointed to the lower one of two similar parts, 20 and 21, which are adjustably connected by means of a rod, 22, the ends of which have engagement with the parts, 20 and 21, respectively, by means of right and left 35 screw-threads. The upper part, 21, is jointed to the outer end of one arm of a lever, 23, which is fulcrumed at 24 to a bracket, 25, projecting from the machine head, the outer end of the other arm of the 40 lever being jointed to the upper end of a link, 26, the lower end of which is jointed to the crank-pin, 3. It is manifest that these details in construction are immaterial to the proper operation of the invention and 45 that the result would be the same if the upper end of the feed-bar, 15, and link, 26, were jointed directly to the lever, 23.

The invention has nothing to do with the looper or shuttle mechanism and hence this 50 mechanism is not fully shown in detail in the drawings but is simply indicated at 27, it being understood that a looper of any suitable form may be used.

Ahead of the needle, 8, is a pair of idle 55 rolls, 28 and 29, between which the work, shown at 30, passes. The faces of the rolls are fluted or corrugated so as to yieldingly but firmly clamp or grip the work and prevent slipping. The upper roll, 28, is carried 60 by a shaft, 31, which is journaled in bearings, 32, rising from the base-plate, 33, of the machine head while the lower roll, 29, is secured to a shaft, 34, journaled at 65 the free ends of swinging links, 35, the other ends of which are pivotally supported

by bearings of any suitable construction carried by brackets, 36, which are, in turn, carried by the base-plate. The rolls derive their movement solely from frictional contact with the work, 30, and in order to insure their rotating in unison, their respective shafts are provided with intermeshing gear wheels, 37 and 38. They are held in contact with the work with the friction necessary to prevent slipping, by coiled springs, 70 39, which surround the stems of adjusting screws, 400, which pass loosely through openings formed through the links, 35, and project into threaded sockets in the base-plate, 33. The springs re-act downward 75 upon the heads of the screws and upward against the links, and their tension may be adjusted by turning the screws in one direction or the other, as may be necessary.

Behind the feed-tappet is a second pair 80 of rolls, 40 and 41, between which the work passes, said rolls having their peripheries fluted or corrugated to prevent slipping. These rolls are positively driven continuously and form a part of the feed mechanism, 85 but the feeding of the work to the needle is not accomplished, either in whole or in part, by their rotation. They are instrumental in feeding the work forward only in that they constitute a clamp which at all times clamps 90 the work and prevents its retrograde movement while the feed-tappet, during its downward movement, is pressing transversely upon the work and thereby deflecting it from its normal plane and drawing forward 95 the length of the work necessary for the next stitch. During the downward movement of the deflector, and the consequent drawing forward of the work, the rolls, 28 and 29, will make a partial turn and stop 100 when the deflector completes its downward movement, so that their rotation will be intermittent, or step by step. But the rotation of the rolls, 40 and 41, is positive and 105 continuous and is produced by power transmitted from the main shaft, 1, through the medium of suitable gearing. As shown in the drawings this gearing may consist of a gear-wheel, 42, carried by the shaft, 1, and meshing with a corresponding gear wheel, 110 43, carried by the upper end of a shaft, 44, the lower end of which carries a worm, 45, which meshes with a worm-wheel, 46, secured to the shaft, 47, of the upper roll, 40, the pitch of the gearing being such that the 115 roll, 40, will turn clock-wise. The lower roll is positively driven counter clock-wise by intermeshing gear wheels, 48 and 49, secured to the shafts, 47 and 50, of the rolls, 40 and 41, respectively. The shafts of the 120 rolls, 40 and 41, are journaled and supported similarly to the rolls, 28 and 29, similar parts accessory to the two pairs of rolls being indicated on the drawings by similar 125 reference characters, with a added as an ex- 130

ponent to the parts accessory to the shafts, 47 and 50, for the sake of distinction. The axis of the shaft, 44, forms angles of 90 degrees with the axes of the shafts, 1 and 47, when the parts are viewed in the direction of these latter axes, and two forms of gearing are shown for transmitting movement from one shaft to the next, but these details also are immaterial and within the scope of 5 the invention any form of gearing or transmitting mechanism may be used in place thereof. The essential characteristic in this respect is that the surface speed of the rolls, 40 and 41, be such that it will exactly equal 10 the length of the work fed forward by each operation of the feed mechanism, which, as before stated, is the exact length required for a single stitch.

Referring to the diagrammatic views, 15 Figs. 3, 4, 5, and 6, Fig. 3 represents the positions of the parts as they are shown in Fig. 1. The needle-bar is at the middle of its up-stroke and the point of the needle is just about to leave the work, 30, which in 20 all of the diagrammatical figures is represented by a single line, and its theoretical normal plane would be represented by a straight line drawn from the bite of the rolls, 28 and 29, to the bite of the rolls, 40 and 41.

25 The feed-bar is at the middle of its down-stroke but the deflector has not reached the normal plane of the work. As the needle-bar completes the last half of its up-stroke, and until it arrives at its upper limit of movement, as shown in Fig. 4, the feed-bar will 30 continue to move downward, the deflector passing below the normal plane of the work, and after engaging the work will continue downward to the lower limit of its movement, as shown in Fig. 4. At the time the 35 needle-bar arrives at the position shown in Fig. 3, there will be more or less slack in the work between the presser-foot, 10, and the rolls, 40 and 41, so that the rotation 40 of the rolls will not draw the work between the rolls, 28 and 29. As soon as the deflector 45 comes in contact with the work, which is clamped by the rolls, 40 and 41, so as to prevent retrograde movement, the continued 50 downward movement of the deflector will draw the proper length of the work forward, between the rolls, 28 and 29, leaving the work in position for the next stitch. The needle-bar will then commence its down- 55 stroke, the first half of which is completed as the shaft, 1, makes a quarter turn, bringing the point of the needle into contact with the work, and simultaneously with this half down-stroke of the needle-bar, the feed-bar 60 will make the first half of its up-stroke, leaving the parts in the positions shown in Fig. 5. As the needle-bar makes the last half of its down-stroke, the needle is thrust 65 through the work into position for the forming of the loop and while this is taking

place the feed-bar will complete the last half of its up-stroke, leaving the parts in the positions shown in Fig. 6. During the next quarter turn of the shaft, 1, the needle-bar will make the first half of its down-stroke, 70 bringing the point of the needle to the normal plane of the work and the feed-bar will make the first half of its up-stroke, 75 returning all of the parts to the positions shown in Fig. 3. It will be observed that during all these operations there will be more or less slack in the work between the presser-foot and the take-up rolls, 40 and 41, so that there is no feeding forward of the work to the needle. It will also be observed that during the entire period when the needle is in the work the foot of the deflector is out of contact with the work, and that after the point of the needle passes above the work and again descends to it, 80 the entire feeding operation is commenced and completed.

In Figs. 3 to 6, and also in Figs. 7 to 10, the upper and lower limits of the travel of the deflector are shown by the dotted lines, 90 52 and 53, respectively, while the upper and lower limits of the travel of the point of the needle are represented by the dotted lines, 54 and 55, respectively. It will be observed that the amplitude of movement 95 of the needle-bar and feed-bar as shown in Figs. 1 to 6 inclusive are equal and that they always move in the opposite directions due to the fact that their movements are taken from opposite sides of one and the 100 same crank-pin, 3. Since these movements are greater than the length of a single stitch, it follows that at all times, excepting when the feed-tappet is acting upon the work to feed the work forward there will be an unrestrained slack between the presser-foot and the take-up rolls. This slack may, however, be avoided by limiting the amplitude of movement of the feed-bar to exactly what is necessary to feed forward exactly the 105 length of the work necessary for a single stitch, and this may be done by using differential mechanism for transmitting movement from one and the same shaft to the needle-bar and feed-bar, respectively. As 110 shown in Figs. 7 to 10, inclusive, this is done by making the arms of the lever, 23, of different lengths. In this event, the lever and needle-bar may be operated by the one and the same crank-pin, as shown in Figs. 1 to 6, inclusive, or by operating them from separate crank-pins, 3^a and 3^b, respectively, having the same throw or degree of eccentricity, as shown in Figs. 7 to 10, inclusive. 115

As shown in Figs. 7 to 10, inclusive, and 120 in Figs. 14 and 15, one of the crank-pins is set 90 degrees in advance of the other and in order that the links, 4 and 26, may pass each other the two pins are in different planes which are perpendicular to the axis 125 130

of the shaft, 1, and the pins are connected by an offset part, 56, or, in other words, they are formed of a single crank-shaped piece. With the crank-pins thus arranged, the needle-bar and feed-bar do not always move in opposite directions, but they will nevertheless move in such manner that the general results above described are obtained. Furthermore, by the use of separate pins for actuating the needle-bar and feed-bar, the desired differential movement, or difference in the amplitude of the movement of the needle-bar and feed-bar may be produced by giving one pin a greater throw or degree of eccentricity than the other, regardless of the relative lengths of the arms of the lever, 23.

It will be noted that in Figs. 3 to 6, inclusive, the deflector is made adjustable by providing it with a stem which occupies a socket in the lower end of the feed-bar and providing a set screw, 57, by which it may be held in any position to which it is adjusted. This will accomplish the same result as the adjustable collar, 19, already described, accomplishes; that is to say, without changing the amplitude of the movement of the deflector it changes the levels of its upper and lower limits of travel so that it contacts with and leaves the work at any desired levels, thus providing for work of different thicknesses as well as for feeding different lengths of the work forward when differently adjusted.

The foregoing description has been confined to a sewing machine having but a single needle, but all of what has been said is applicable to a machine having a plurality of needles. In Figs. 2 and 11, three needles are shown, arranged side by side, or in a "gang", and the number may be increased indefinitely. In order to increase the number from one up, it is simply necessary to increase the lateral extent of the deflector and the presser-foot and correspondingly increase the lateral extent of the needle-clamp ^{8b}, all of which is shown in Fig. 2 sufficiently for the purposes of this application.

What I claim as new and desire to secure by Letters Patent is:

1. A sewing machine having, in combination, a needle, means for operating it, and feed mechanism, said feed mechanism having a clamp for constantly engaging the work and at all times positively holding it and preventing its retrograde movement, a deflector engaging the work between the needle and clamp, and means for reciprocating the deflector in a direction transverse to the normal plane of the work during intervals while the needle is out of the work.

2. A sewing machine having, in combination, a needle, means for operating it, and

feed mechanism, said feed mechanism having a clamp for constantly engaging the work and at all times positively holding it and preventing its retrograde movement, a deflector engaging the work between the needle and clamp, means for reciprocating the deflector in a direction transverse to the normal plane of the work during intervals while the needle is out of the work, and continuously operating means located in rear of the deflector for taking up the slack in the work in rear of the needle. ⁷⁰

3. A sewing machine having, in combination, a needle, means for operating it, a presser-foot, and feed mechanism independent of the presser-foot, said feed mechanism having a clamp in rear of the presser-foot adapted to constantly engage the work and at all times positively preventing its retrograde movement, a deflector engaging the work between the clamp and presser-foot, and means for reciprocating the deflector in directions transversely to and across the normal plane of the work for deflecting it from said plane and thereby drawing it forward, step by step, during intervals while the needle is out of the work. ⁸⁰

4. A sewing machine having, in combination, a needle, means for operating it, a presser-foot, and feed mechanism independent of the presser-foot, said feed mechanism having a clamp in rear of the presser-foot adapted to constantly engage the work and at all times positively preventing its retrograde movement, a deflector engaging the work between the clamp and presser-foot, means for reciprocating the deflector in directions transverse to the normal plane of the work for deflecting it from said plane and thereby drawing it forward, step by step, during intervals while the needle is out of the work. ⁹⁰

5. A sewing machine having, in combination, a needle, means for operating it, and feed mechanism, said feed mechanism having a deflector adapted to engage the work in rear of the needle, means for reciprocating said deflector in directions transverse to the normal plane of the work for deflecting it from said plane and intermittently drawing it forward, step by step, during intervals while the needle is out of the work, a pair of combined clamping and take-up rolls engaging the work in rear of the deflector, and means for continuously revolving at least one of said rolls and thereby taking up the slack in the work in rear of the needle and also preventing its retrograde movement. ¹⁰⁰

6. A sewing machine having, in combination, a needle, means for operating it, and feed mechanism, said feed mechanism having, a head of the needle, means for firmly ¹¹⁰ ¹¹⁵ ¹²⁰ ¹²⁵ ¹³⁰

but yieldingly clamping the work and retarding its forward movement, means in rear of said yielding clamp for positively and at all times clamping the work and preventing its retrograde movement, a deflector engaging the work between said two sets of clamping means, means for moving the deflector in directions transverse to the normal plane of the work as it passes from one to the other of said clamps and thereby deflecting it from said plane and suddenly drawing it forward past the yielding clamp at an interval when the needle is out of the work, and continuously operating means in rear of the deflector for taking up the slack in the work between the two clamps.

7. A sewing machine having, in combination, a needle, means for operating it, and feed mechanism, said feed mechanism having a pair of rolls located in rear of the needle, between which the work passes, means for constantly forcing said rolls toward each other for at all times clamping the work, means for positively and continuously revolving at least one of said rolls in one direction and preventing its retrograde movement, thereby taking up the slack in the work in rear of the needle, a deflector adapted to engage the work between said rolls and the needle, and means for reciprocating said deflector in directions transverse to the normal plane of the work for deflecting the work from said plane and intermittently drawing it forward, past the needle, step by step, during intervals when the needle is out of the work.

8. A sewing machine having, in combination, a needle, means for operating it, and feed mechanism, said feed mechanism having a pair of rolls located in rear of the needle, between which the work passes, means for constantly forcing said rolls toward each other for at all times clamping the work, means for positively and continuously revolving at least one of said rolls in one direction and preventing their retrograde movement, a deflector located ahead of said rolls and movable in directions transverse to the normal plane of the work, and means ahead of said deflector for engaging the work and yieldingly holding it taut.

9. A sewing machine having, in combination, a plurality of needles, means for operating them, and feed mechanism, said feed mechanism having means for positively and at all times clamping the work in rear of the needles, a reciprocating deflector adapted to engage the work between said clamping means and the needles, means for yieldingly clamping the work ahead of said deflector, and means for operating the deflector to draw the work forward at intervals while the needles are out of the work, the foot of the deflector being extended laterally to cross a plurality of the rows of stitches.

10. A sewing machine having, in combination, a needle, means for operating it, and feed mechanism, said feed mechanism having means for positively and at all times clamping the work in rear of the needle and for preventing the retrograde movement thereof, means for continuously taking up the slack in the work between the needle and said clamping means, a reciprocating deflector adapted to engage the work between the needle and the clamping means last aforesaid, means for yieldingly clamping the work ahead of the feed-bar, and means for operating the deflector to draw the work forward past the needle at intervals when the needle is out of the work.

11. A sewing machine having, in combination, a needle, means for operating it, and feed mechanism, said feed mechanism having a pair of rolls located in rear of the needle, between which the work passes, means for forcing said rolls toward each other for clamping the work, means for positively revolving at least one of said rolls, a reciprocating deflector adapted to engage the work between said rolls and needle, means for yieldingly clamping the work ahead of said deflector, and means for reciprocating the deflector into engagement with the work and drawing it forward at an interval while the needle is out of the work.

12. A sewing machine having, in combination, a needle, means for operating it, and feed mechanism, said feed mechanism having a pair of rolls located in rear of the needle, between which the work passes, means for forcing said rolls toward each other, intermeshing gear wheels for transmitting movement from one of said rolls to the other, means for positively revolving at least one of said rolls, a deflector adapted to engage the work ahead of said rolls, means for operating the deflector to draw the work forward at an interval while the needle is out of the work, and means for yieldingly clamping the work ahead of the feed-tappet.

13. A sewing machine having, in combination, a needle, means for operating it, and feed mechanism, said feed mechanism having a pair of rolls located in rear of the needle, between which the work passes, means for positively revolving at least one of said rolls, a deflector adapted to engage the work between said rolls and needle, means for operating the deflector to draw the work forward at an interval while the needle is out of the work, a pair of idle rolls located ahead of the needle between which the work passes and means for yieldingly forcing said rolls toward each other.

14. A sewing machine having, in combination, a needle, means for operating it, a presser-foot, means for yieldingly forcing it downward and feed mechanism, said feed mechanism having means adapted to engage

- the work in rear of the presser-foot, means for operating said feeding means to feed the work forward during an interval while the needle is out of the work and means engaging the work in rear of said feeding means for taking up the slack in the work in rear of the presser-foot.
15. A sewing machine having, in combination, a needle, means for operating it, a presser-foot, means for yieldingly forcing it downward and feed mechanism, said feed mechanism having feeding means adapted to engage the work in rear of the presser-foot, means for operating said feeding means to intermittently feed the work forward, step by step, during an interval while the needle is out of the work, and means for taking up slack in the completed work after the feeding operation is completed.
- 20 16. A sewing machine having, in combination, a needle, means for operating it, a presser-foot and feed mechanism, said feed mechanism having feeding means adapted to engage the work in rear of the presser-foot, means for operating said feeding device to intermittently feed the work forward, step by step, during an interval while the needle is out of the work, means for taking up slack in the completed work after the feeding operation is completed, and means for continuously operating said take-up means.
- 25 17. A sewing machine having, in combination, a needle, means for operating it, a presser-foot and feed mechanism, said feed mechanism having a pair of rolls located in rear of the presser-foot, between which the work passes, means for forcing said rolls toward each other for clamping the work, means for positively and continuously revolving at least one of said rolls, feeding means adapted to engage the work between said rolls and the presser-foot, and means for operating said feeding means for drawing the work forward at an interval while the needle is out of the work.
